UNITED STATES PATENT OFFICE.

ORVILLE L. ROUTT, OF LOS ANGELES, CALIFORNIA.

PROCESS OF MAKING PLASTER BOARD.

Application filed August 23, 1922. Serial No. 583,729.

My invention relates to a new process for making plaster board and is capable of use in connection with a wall board machine, whereby such a machine can, with the use of 5 my invention, be readily and comparatively inexpensively converted into a plaster board machine, thus making it possible for one machine to be used for making wall board or plaster board, as desired.

10 By my improved process, I am able to make a plaster board with smooth opposite sides, one side of which is provided with openings through the face covering and at which openings sufficient of the plastic material is removed during the process to form 15 a rough and slightly hollowed area which forms the bond between the plaster board and the coat of plaster applied thereto. By the removal of a small amount of the plastic 20 material at the openings through the surface covering, there is provision for the attachment of the plaster coat and at the same time the surface of the plaster board is smooth and free of any projections to interfere with piling of the same. By my improved process, I am able to manufacture 25 such a plaster board with a minimum of machinery and expense.

In order to clearly explain my invention, 30 I have illustrated one method of carrying out the process on the accompanying sheet of drawings, which I will now describe.

Figure 1 is an edge, or diagrammatic view 35 of an apparatus for carrying out my improved process;

Figure 2 is an enlarged sectional view of 40 revolving dies for cutting the openings through one sheet of the covering for the plaster board;

Figure 3 is a fragmentary sectional view, 45 enlarged, showing the bottom sheet, the plastic material, the top sheet with the openings therethrough, and the forming sheet; and

Figure 4 is a view of the face of the plaster board.

Referring more in detail to the drawings, 1 designates a forming belt or carrier, running around a roller, 2. This may be of any 50 suitable construction. A roll of paper, 3, is provided for use in forming the bottom sheet or surface of the plaster board and this is carried forwardly on the carrier 1. The plastic material, 4, is fed from a hopper, 5, or 55 other suitable feeding apparatus, on to the sheet 3, as illustrated.

In the present showing of the invention for illustrative purposes, instead of using a separate roll of paper for what I will call the forming sheet, I use another roll of paper 60 similar to that shown at 3, and carry it around a plurality of rollers and pass it twice under the machine roller, 6, said second roll of paper being designated 7. I will now trace the course of the paper from the second roll 7. After passing around the roller 6, it passes forwardly and upwardly around rollers, 8, 9 and 10, and thence between roller dies, 11 and 12, which cut perforations or 65 openings, 13, through the sheet, as will be 70 clear from the fragmentary view in Fig. 4, said openings being here shown as of diamond shape, but which can be of any desired form. From the dies, said sheet passes again around the roller 6, and on top of the plastic 75 material 4, the upper lap of said paper covering the openings as the sheets pass under the roller 6 and forming the plastic material into a uniform layer or sheet. As the upper layer or lap of the paper, which I will designate 7^a, leaves the perforated sheet and passes up to the take-up rollers 8, 9 and 10, a certain amount of the plastic material, 80 through the perforations or openings 13, adheres to said upper sheet 7^a, and is brushed 85 therefrom by means of a revolving brush, 14, above the roller 8, as shown in Fig. 1. This leaves a hollowed condition in the plastic material at the opening in the face sheet, as indicated at 7^b, thus providing an efficient 90 means for forming a bond between the plaster board and a coat of plaster when applied thereto, and at the same time the surface of the plaster board is smooth and can be piled 95 flat, one sheet upon another without any danger of breaking off projections from the surface thereof.

It will be clear, I believe, from the showing made, that my invention can be applied to a wall board machine by the simple provision 100 of means for putting the openings through the sheet of paper or other covering and then providing a forming or covering sheet to pass under the roller 6, above the sheet having the openings therein to prevent the 105 plastic material from pressing through said openings, and for lifting out a small portion of the plastic material, through the opening, as the top sheet moves away therefrom.

110 I am aware that various ways can be used for accomplishing the process or function

described and that changes can be made in the showing made, and I do not, therefore, limit my invention to the showing made except as I may be limited by the hereto appended claims.

I claim:

1. The process of manufacturing plaster board which consists in pressing a surface sheet having openings therethrough on to plastic material, with a lap of said same sheet above the portion having the perforations therein to overlap said perforations, and causing the plastic material at the openings to be roughened by removing the lap of said sheet from the perforated sheet.
2. The process of making plaster board consisting of forming plastic material into

sheets between two sheets of paper, one of said sheets being doubled as it is pressed upon said plastic material, the lap of said paper being pressed directly upon said plastic material being perforated and the other lap of said paper covering said perforations as said plastic material is rolled into sheets, and being pulled away therefrom after said plastic material is formed into sheets and removing small quantities of said plastic material through said perforations, whereby to roughen the same to receive plaster thereupon.

Signed at Los Angeles, California, this 17 day of August, 1922.

ORVILLE L. ROUTT.
